E. K. LELAND

HAIR STRAIGHTENING TOOL

Filed Feb. 20, 1925

FIG. 1

FIG. 2

FIG. 3

INVENTOR.

Edna King Leland,
BY Walter N. Haskell,

her ATTORNEY.

UNITED STATES PATENT OFFICE.

EDNA KING LELAND, OF MORRISON, ILLINOIS.

HAIR-STRAIGHTENING TOOL.

Application filed February 20, 1925. Serial No. 10,635.

My invention has reference to a hair-straightening tool, and has for its purpose to assist in taking the twists and bends out of kinky hair which is characteristic of some races of people.

In the drawings:

Fig. 1 is a perspective of the preferred form of the invention.

Fig. 2 is a similar view of a modified form thereof.

Fig. 3 is a cross-section through the jaws 1 and 2, with said jaws in closed position.

The device comprises a pair of jaws 1 and 2, pivotally united as at *a*, and fitted, respectively, with handles 3 and 4. The inner face of the jaw 1 is flattened, as at 5, and fixed therein at intervals are pins 6. The adjacent face of the jaw 2 is similarly flattened, as at 7, and said face is provided at intervals with openings 8, adapted to receive the pins 6.

The jaw 1 is preferably of a solid construction, and the jaw 2 of a shell formation, as shown in Fig. 3. In use, the jaws are engaged with a strand of hair, and the tool drawn outwardly, the kinks being removed partly by the flat faces of the jaws, and partly by the pins 6, which prevent the hair from curling up again as it is drawn between the jaws. The operation is improved by first heating the jaws, in the manner of a curling iron.

To prevent the hair from being too tightly clamped between the jaws 1 and 2, a stop 9

is provided at the end of the jaw 2, which limits the distance to which the jaw 1 may be closed thereon.

In Fig. 2 is shown a more simple form of the device, embracing a pair of jaws 10 and 11, having cooperating faces 14 and 15, said jaws being pivotally united as at *b*, and provided with handles 12 and 13, by means of which they can be operated. The manner of using such modified form is similar to that of the tool first herein described, the hair being drawn between the flat faces, but the pins 6 and openings 8 being omitted.

In case the operation is not at first fully successful, it may be repeated until the desired results are secured.

What I claim and desire to secure by Letters Patent, is:

1. In a device of the class described, a pair of jaws pivotally united, and provided with means for operation thereof, cooperating faces on said jaws, and interengaging pins and openings carried by said jaws at regular intervals.

2. A device of the class described, comprising a pair of jaws, pivotally united, and operating handles attached thereto, said jaws being provided with cooperating flattened faces; inter-acting pins and openings in said jaws; and means for limiting the degrees to which said jaws may be closed.

In testimony whereof I affix my signature.

EDNA KING LELAND.
